[57] **CLAIM**

I claim the ornamental design for a heat retaining tube for use in a semiconductor wafer heat processing apparatus, as shown and described.

DESCRIPTION

FIG. 1: a perspective view of a heat retaining tube for use in a semiconductor wafer heat processing apparatus;
FIG. 2: a top plan view thereof;
FIG. 3: a front elevational view thereof;
FIG. 4: a cross sectional view thereof taken along line IV—IV in FIG. 3;
FIG. 5: a cross sectional view thereof taken along line V—V in FIG. 3;
FIG. 6: a left side view thereof;
FIG. 7: a right side view thereof;
FIG. 8: a bottom plan view thereof; and,
FIG. 9: a rear elevational view thereof.
